INSULATED JUG OR THE LIKE

Herbert M. Piker, Wyoming, Ohio, assignor to Hamilton-Skotch Corporation, Hamilton, Ohio, a corporation of Ohio

Filed Aug. 30, 1961, Ser. No. 66,554

Term of patent 14 years

(Cl. D58—17)

Fig. 1.

Fig. 2.

FIG. 1 is an elevational view of one of two opposite sides of an insulated jug or the like, showing my new design;

FIG. 2 is an elevational view thereof, shown turned 90 degrees from FIG. 1;

FIG. 3 is a top plan view thereof; and

FIG. 4 is a bottom plan view thereof.

The opposite faces are identical with those disclosed and identified in FIGS. 1 and 2.

I claim:

The ornamental design for an insulated jug or the like, substantially as shown and described.
